UNITED STATES PATENT OFFICE.

FRANK J. DOLAN, OF BROOKLYN, NEW YORK, ASSIGNOR TO JOSEPH M. PRICE, OF NEW YORK, N. Y.

BOX.

Application filed November 18, 1922. Serial No. 301,890.

To all whom it may concern:

Be it known that I, FRANK J. DOLAN, a citizen of the United States, residing at 1732 58th Street, Brooklyn, in the county of 5 Kings, State of New York, have invented certain new and useful Improvements in Boxes; and I do hereby declare the following to be a full, clear, and exact description of the invention, such as will enable others 10 skilled in the art to which it appears to make and use the same.

This invention relates to improvements in boxes and more particularly to boxes of the cylindrical or tubular type. Boxes of the 15 kind are widely used commercially for the distribution of merchandise, such as candy, cosmetics, etc., which is to be consumed directly from the box and for such purposes, it is usual to provide a box which may be 20 placed on display and which by its attractive appearance, adds to the marketability of its contents. Tubular or cylindrical boxes are, therefore, highly desirable for such use, not only on account of their attractive and 25 convenient form but also on account of their adaptability to surface decoration. The cost of manufacturing this type of box is low and the decorative material may be readily placed in position on the box proper.

30 Tubular boxes of the kind referred to are commonly constructed of a plurality of telescoping rings and heads, the latter being held in place by the rings by suitable means. The rings which form these cylindrical side 35 walls are usually cut from long tubes formed by winding paper strips spirally about a mandrel and it is customary, in order to give the tube a finished appearance to construct it of several layers formed on a center 40 or base layer, the inner and outer faces of which are covered by finishing layers of a lighter and higher grade material. Inasmuch as the rings of which the boxes are to be constructed are cut from such tubes after 45 the tubes have been wound, it will be evident that the rings will have an unfinished edge which is likely to become ragged and torn unless some protective means is employed. The addition of a protective strip for such 50 a purpose adds to the expense of construction both as to labor and materials, and it is therefore desirable to provide some other arrangement by which the edges of the rings forming the body and cover may be protected.

In providing a box having a decorated side wall, it is also desirable to provide a construction in which a decorative strip may be placed in position thereon in a single 60 operation. In ordinary constructions, the box is formed by a body and cover, the side walls of these parts being placed in registering relation when the box is closed. It is clear that a single decorative strip cannot be applied in a single operation to both the 65 body and the cover when their edges are in abutment inasmuch as the strip would have to be cut to permit the opening of the box and in this way the decorative effect would be lost. It is also unsatisfactory to provide 70 a box of the character just mentioned with decorative strips which are applied separately to the side walls of the body and the cover, owing to the difficulty of applying this material so that the decorative pattern 75 in the two strips will properly register.

It is therefore desirable to devise a box construction in which the above difficulties may be obviated in so far as possible, and the present invention provides a box having a 80 body and a cover, the cover being of such size and shape as to fit within the end of the body and to be supported in that position with the upper surfaces substantially 85 flush with the upper edge of the side walls 90 of the body. In this box I have further provided a body composed of a plurality of rings to form the side walls thereof and the outer ring is so constructed as to form a protective edge bead which gives the body 95 a smooth finished appearance. The cover which is constructed of a side wall ring and one or more heads placed therein, is also provided with edge beads and is so constructed that these beads will serve to protect and center the cover when it is inserted 100 in place. Within the body of the box I provide an abutment for supporting the cover, which is so placed as to cause the edge beads of the cover and of the body to 105 lie in adjacent flush position when the box is closed, thus adding to the finished and attractive appearance. I have also constructed the abutment so that it may be used to support a diaphragm so that the contents 110 of the box may be protected from contamination and prevented from being wasted during distribution, this diaphragm being of light material which may be readily removed when it is desired to remove the con-

tents of the box. Furthermore, the cover of the box is so constructed that the head lies at a substantial distance from the abutment so that when a diaphragm is provided, 5 there is formed a small compartment between the diaphragm and the head. In the use of the box for the distribution of cosmetic materials, such as face powder, this compartment offers a convenient place for 10 disposing of the powder puff within the box but out of contact of the contents. When the diaphragm is removed and the contents are to be used, the puff after use may be placed on top of the powder itself and 15 when the cover is replaced there is no likelihood of the material being spilled or the puff falling out.

The present invention consists of the constructions and of the combinations of parts 20 which are now to be described. For a clear understanding of the invention, reference will be made to the drawings, in which:

Fig. 1 shows a perspective view of a box constructed in accordance with this invention;

Fig. 2 is a longitudinal cross-sectional view thereof, and

Fig. 3 is a cross-sectional view similar to Fig. 2, certain parts having a modified construction and other parts being shown in 30 partial side elevation.

With reference now to the drawings in which similar reference characters are used to designate similar parts throughout the 35 several views, the box is formed of a body 1, which is in turn formed with a side wall comprising an inner ring 2 and an outer ring 3, the latter being provided with an external decorative strip 4.

40 The inner ring 2 is ordinarily constructed of a heavy paper stock so as to give strength and rigidity to the side wall, and the outer ring 3 will be noted to project at its marginal edges beyond the ends of the inner ring 2, and these marginal edges are in-turned, as at 5 and 6, to provide substantially circular edge beads. These beads overlap the ends of the inner ring 2 and are of such size that the internal diameter of the 45 outer ring across the beads is substantially equal to the internal diameter of the inner ring, the beads serving to conceal the inner ring and to protect its ends.

The body of the box is provided with a 50 head 7, which lies, as will be clear in Fig. 2, against one end of the inner ring 2, being held in that position by the bead 6, which is turned over after the head has been placed in position. It will thus be seen that the 55 lower edge bead not only serves the purpose of providing a finished edge construction for the outer ring 3 but in turn serves to lock the head of the body in position.

The second member which forms part of 60 the box is the cover 8, this cover being

formed of one or more heads 9 and 10, and a side wall ring 11. This side wall ring is provided with an edge bead 12, formed by inwardly turning the edge of the wall upon itself. At the lower end of the ring, the 70 wall is folded back upon itself, as indicated at 13, and this inwardly folded portion 14 is led along the inner face of the wall to a point near the other end, where the edge is turned outwardly again, as shown at 15, so 75 as to conceal the raw edge. It will be noted upon reference to the drawings that this in-folded portion 14 is preferably held in spaced relation to the portion 11 and by producing the fold in this way the entering edge of the wall of the cover is given a degree of elasticity which makes it easier to insert the cover within the body, and which also insures that the cover will be firmly held in place therewithin. The head, 80 which may consist of one or more discs, is held in place by the side wall with its edges locked in position between the bead 12 and the folded portion 15. It will thus be seen that while the head is locked firmly in position, the edges of the side wall on either side thereof are rounded so as to give a smooth finished appearance, thus protecting the side wall and preventing fraying or other damage thereto as the cover is placed 85 in position.

As has been explained, it is intended in the present construction, that the cover be disposed within the side walls of the body when the box is closed. Inasmuch as in such 90 an arrangement there will always be wear when the cover is placed in position or removed, it is desirable that this wear be taken up by smooth rounded surfaces in so far as possible. This object has been attained by the construction just described and the bead 5, which serves as a protecting edge for the body will not only assist in centering the cover when the latter is to be placed in position but will also, by reason of its finished 95 surface, prevent wear. As the cover is to be placed in the position shown, it is obvious that some provision must be made for its easy removal and this is taken care of by the means of a suitable handle formed, if desired and as shown at 16, of a loop of 100 ribbon, the ends of which are inserted through an aperture in the head and anchored to the inner face thereof.

In the box here illustrated, the head of 105 the cover is formed of two discs designated as 9 and 10. The outer member 9 is formed of a sheet of material of slightly greater diameter than the internal diameter of ring 11, consequently when the member 9 is inserted in position it will have an arched 110 appearance. It is clear of course that the head could be made of a single member only but the construction shown adds to the attractive appearance of the box and as has 115 120 125 130 135

been explained, the appearance is a matter of considerable importance in boxes of this kind.

In order to provide an abutment to support the cover within the body, I have here made use of an additional tubular member which is placed within the body and which is extended to such a height that its upper edge will serve as a support for the cover and maintain the latter in the desired position. It will be clear that such an abutment might be readily formed as a part of the body side wall, or in various other ways, but I have found the tubular member easily manufactured and, in some instances, preferable to other arrangements inasmuch as it may readily be adapted to provide a protective cover for the contents. When it is desired to use the box for the material which should be closely confined, prior to its use, as by means of a diaphragm, I form the tubular member in accordance with the construction illustrated in Fig. 2, wherein this member consists of inner and outer rings 17 and 18. It will be noticed that the outer ring 18 extends a slight distance beyond the inner ring and this edge is inwardly turned at 19 to form a bead. This bead performs a dual function in that it not only protects the edge of the inner ring but in turn provides a comparatively large bearing surface for the cover. This bead will preferably be of such size that inwardly it lies flush with the inner surface of the inner ring, thus obviating the possibility that the material may be caught behind it or that ingress to the box may be made difficult. In providing the tubular member with a diaphragm, I first form the outer ring with a bead, then place a sheet of light material, such as a bond paper, over the edges of the inner ring and then cause the inner ring to be forced into position within the outer ring. As shown in Figure 2, the diaphragm designated as 20 is held in position along its peripheral edge by being gripped between the inner and outer rings and the upper edge of the inner ring further grips the inner edge of the diaphragm by forcing it against the inner face of the bead. This serves to hold the diaphragm taut and in order to fill the box the tubular member is removed and inverted. The material is then placed therein and the body of the box, held inverted, is passed over the tubular member. The tube may then be restored to the upright position whereupon the contents will be safely held in the bottom of the body.

In the use of the box for the distribution of cosmetic materials, it will be seen by the construction I have described, the inner head 10, as shown in Fig. 2, lies at a considerable distance from the diaphragm 20, when the cover is in position. In the compartment so formed a powder puff 21 may be conveniently disposed and when the diaphragm is

removed so as to make available the contents, the powder puff will be permitted to rest upon the powder itself.

In Figure 3, there is illustrated a box constructed in accordance with the general principles above outlined, but slightly modified for use for the distribution of merchandise which is not subject to loss, such as would ordinarily occur with pulverulent material. In this construction it is found unnecessary to provide a diaphragm and the abutment which serves to support the cover is constructed of a single ring of such size as to lie in contact with the inner wall of the body and provided with an internally disposed bead along its upper edge. A box of this type is particularly useful for shipping candy.

It will be seen that the box construction which I have just described and illustrated is well adapted to serve the various purposes which have been suggested and may be easily constructed with a minimum of labor cost for decoration. After the side walls have been formed, it is only necessary to paste or otherwise affix the decorating material to the outer surface thereof. The box has an unusually attractive appearance inasmuch as there are provided two finishing beads which lie flush with each other around the periphery of the cover, one being formed on the body and the other on the cover and by constructing these beads of material of contrasting colors, a pleasing effect is arrived at. By constructing the box so that all the exposed edges are formed as beads, there not only results a finished appearance but furthermore the box may be used indefinitely without wear along the engaging surfaces. By using rings of suitable diameters, for the cover and the body, it is possible to give these parts smooth beads which hold the cover firmly in position and also insure that the material contained in the box shall not be lost.

While I have shown one form of construction in accordance with the broad principles of the invention set forth, it will be understood that the constructions shown in the drawings are for illustrative purposes only and are not to be considered in a limiting sense. Obviously, many changes lying within the scope of the invention would suggest themselves to one skilled in the art.

I claim:

1. A box of the class described comprising, in combination, a body and a cover, and a tubular member disposed within said body and adapted to support said cover therewithin, said cover having a side wall marginally bent upon itself to provide protective edges and said tubular member having a bead formed on its cover-supporting margin.

2. A box of the class described, compris-

ing in combination a body formed of an outer ring, an inner ring, and a head, the head resting on the end of the inner ring and the head and inner ring being held in place by inturned portions of the outer ring, a cover having a maximum diameter substantially equal to the interior diameter of the said body and adapted to be received therein, this cover being formed of a ring and a head closing the ring, and a separable tubular member disposed within the body and forming an abutment on which the cover rests.

3. A box of the class described comprising in combination a body and a cover adapted to be fitted therein, said cover having its side wall formed of a ring reversely folded along its entering edge to provide a rounded rim, the opposed portions of the side wall being in spaced relation adjacent the entering edge, and an abutment disposed within the body to support said cover therewithin.

4. A box of the class described, comprising in combination a body and a cover adapted to be fitted therewithin, said cover being composed of a ring and a head, one edge of said ring having an internal bead, the other end of the ring being reversely folded upon itself with the infolded portion of the ring spaced from the outer portion, said head being held between the bead and the folded edge, and an abutment disposed within said body to support the cover therewithin.

5. A box of the class described comprising, in combination a body and a cover adapted to be fitted therewithin, and the exposed edges of the side walls of said parts being provided with beads and an abutment disposed within said body to support said cover, said abutment being so constructed and arranged as to maintain the beads of said side walls flush with each other.

6. A cover for a box of the class described comprising a ring and a head, said ring being provided at one end with an inturned bead, and the other end of the ring being folded back upon itself to provide two walls in spaced relation, the head being supported intermediate the ends of said ring between its marginal edges.

7. A cover for a box of the class described comprising a ring and a head, said ring being formed at one end with a marginal bead, the other end being folded back upon itself to provide a portion having two walls separated by an air space, the extreme end of the infolded portion being turned outwardly to close this air space, and the head being held between the bead and the outwardly folded portion.

8. A cover for a box of the class described, comprising a ring having its mar-

ginal edges folded so as to provide a sidewall of two thicknesses separated by an air space and a head mounted between the opposed marginal edges.

9. A box of the class described comprising in combination a body formed of inner and outer rings and a head, the outer ring having its edges bent to form beads overlying the edges of said inner ring, a removable cover adapted to be fitted in one end of said body and an abutment disposed on the inner wall of said body to support said cover in relation thereto.

10. A box of the class described comprising in combination a body formed of inner and outer rings and a head, said outer ring having its edges inturned to form beads, said inner ring lying between said beads and having an internal diameter substantially equal to that of said beads, and said head being held between one end of said inner ring and the adjacent bead, a cover adapted to be fitted into said body and an abutment in said body to support said cover in position therein.

11. A box of the class described, comprising in combination a body having its side wall formed of inner and outer rings, said outer ring having one edge inturned to form a bead concealing the edge of said inner ring and of an internal diameter substantially equal to that of said inner ring, a removable cover having a side wall provided with a marginal bead and an abutment disposed within said body to hold said cover with its side wall bead flush with said ring bead.

12. A box of the class described comprising the combination of a body, a cover adapted to be fitted within the side wall of the body and comprising a ring and a head closing the ring and mounted between the ends thereof, and a separable tubular member disposed within the body against the side wall thereof and providing an abutment on which the ring of the cover may rest, the said tubular member being provided with a frangible diaphragm which closes it.

13. A box of the class described, comprising in combination, a body formed of an inner ring, an outer ring, and a head, the head resting on the end of the inner ring and being held in place by inturned portions of the outer ring, one of which bears against the head and the other against the remote end of the inner ring, a cover consisting of a ring and a head closing the ring and held between the inturned ends thereof, this cover having its maximum diameter substantially equal to the interior diameter of the body, and adapted to be received in the end thereof, and a tubular member disposed within the body against the side wall of the latter and resting on

the head closing the body, the upper edge of this tubular member providing an abutment on which the cover rests.

14. A box of the class described comprising, in combination, a body composed of a head and side wall extending beyond said head, and a cover adapted to be fitted within the body and having an extended side wall lying in contact with the side wall of the body when the cover is in place therewithin, the cover side wall being formed adjacent its entering edge of folded portions held in spaced relation.

15. A box member comprising an inner ring, an outer ring telescoped thereover, a head lying across one end of the inner ring, and within the outer ring, and beads formed on the ends of the outer ring, one of these beads serving to confine the head in position, and the other to overlie and conceal the end of the inner ring, the internal diameter of the body across the latter bead be-

ing substantially equal to the internal diameter of the inner ring.

16. A box of the class described comprising the combination of a body, a cover adapted to be fitted within the side wall of the body and comprising a ring lying in contact with the side wall when the cover is in place, and a head closing the ring and held within the ring between the ends thereof adjacent one of said ends, and a separable tubular abutment disposed within the body to support the cover in place therein and provided with a frangible diaphragm, the relative positions of the diaphragm and the head of the cover when the latter is in place within the box being such as to provide a compartment between the head and the diaphragm.

In testimony whereof I affix my signature.

FRANK J. DOLAN.
